DESIGN FOR A COMBINED HOOD AND BRACKET FOR HAIR DRIERS

Eugene F. Suter, New York, Marcel J. Suter, Bronxville, and Hans Beike, Glendale, N. Y., assignors to Eugene, Ltd., New York, N. Y., a corporation of New York

Application August 31, 1940, Serial No. 94,758

Term of patent 14 years

To all whom it may concern:

Be it known that we, Eugene F. Suter, a resident of New York, county and State of New York, and Marcel J. Suter, a resident of Bronxville, county of Westchester and State of New York, both citizens of the United States, and Hans Beike, a citizen of the Republic of Germany, residing in Glendale, county of Queens and State of New York, have invented a new, original, and ornamental Design for a Combined Hood and Bracket for Hair Driers, of which the following is a specification, reference being had to the accompanying drawing, forming a part thereof.

The figure is a side perspective view of a combined hood and bracket for hair driers embodying our new design, the opposite side being substantially the same as the side shown.

We claim:

The ornamental design for a combined hood and bracket for hair driers, substantially as shown and described.
